CLAIM

The ornamental design for a retail display counter, as shown and described.

DESCRIPTION

FIG. 1 is a perspective view of a retail display counter showing our new design;

FIG. 2 is a front elevational view thereof;

FIG. 3 is a top plan view thereof;

FIG. 4 is a rear elevational view thereof; and,

FIG. 5 is a right side elevational view as seen when in use; the left side being a mirror image thereof.

The bottom of the display counter forms no part of the claimed design.
